CLAIM

The ornamental design for a shoe sole, as shown and described.

DESCRIPTION

FIG. 1 is a perspective view of a shoe sole showing my new design

FIG. 2 is a front elevational view of the shoe sole of FIG. 1; FIG. 3 is a rear elevational view of the shoe sole of FIG. 1; FIG. 4 is a right side elevational view of the shoe sole of FIG. 1;

FIG. 5 is a left side elevational view of the shoe sole of FIG. 1;

FIG. 6 is a bottom plan view of the shoe sole of FIG. 1; and, FIG. 7 is a top plan view of the shoe sole of FIG. 1.

The broken line around the inner perimeter in FIG. 7 illustrates the portion of the design that forms no part of the claim.
